HYDRODYNAMIC MACHINE

Walter Ferris, Milwaukee, Wis., assignor to The Oilgear Company, Milwaukee, Wis., a corporation of Wisconsin

Application October 20, 1939, Serial No. 360,353

9 Claims. (Cl. 103—161)

This invention relates to hydrodynamic machines of the type which will function as pumps when driven mechanically and will function as motors when supplied with motive liquid. Since the same machine will function as either a pump or as a motor, the invention will be explained as applied to a pump but it is to be understood that the invention is equally applicable to a motor.

The type of pump in which the invention is ordinarily embodied has a plurality of pistons fitted in cylinders which are arranged in a rotatable cylinder barrel either directly upon or at a small angle to the radii thereof and the outer ends of the pistons engage an annular reaction surface which is arranged around the cylinder barrel, the axis of the reaction surface being offset from the axis of the cylinder barrel when the pump is delivering liquid.

The cylinder barrel has ordinarily been journaled upon a valve shaft or pintle having passages extending therethrough and two ports formed therein diametrically opposite each other for conveying liquid to and from the cylinders which communicate with the two ports alternately as the cylinder barrel rotates so that the pintle coats with the cylinder barrel to form the main valve.

The pintle ordinarily constitutes the sole support for the cylinder barrel and therefore provides the sole reaction for the pumping forces so that an increase in pump pressure causes more or less deflection of the pintle.

Such a machine has as an inherent characteristic thereof a small amount of slip or leakage which consists in part of liquid that escapes from the high pressure pintle port and spreads over the surface of the pintle to form a lubricating film between it and the inner surface of the cylinder barrel. A part of this liquid flows into the low pressure pintle port and a part thereof escapes from the ends of the cylinder barrel, thereby reducing the efficiency of the machine.

The cylinder barrel is ordinarily closely fitted upon the pintle and one part of the lubricating film adheres to the inner surface thereof and another part of the film adheres to the pintle so that rotation of the cylinder barrel causes shearing of the film. That is, the inner part of the film remains stationary and the outer part moves with the cylinder barrel so that the two parts of the film are constantly being split during rotation of the cylinder barrel. It has been found that shearing the film consumes a substantial part of the power required to rotate the cylinder barrel, thereby further reducing the efficiency of the machine.

It has been found in practice that, when a cylinder barrel fitted upon a pintle as above described is run very slowly under a substantial load, the lubricating film between the cylinder barrel and the pintle is not properly maintained and the frictional drag is materially increased. If rotation ceases when the cylinder barrel is under pressure, as when a motor stalls under its load, the film may be entirely squeezed out and cause the cylinder barrel to grip the pintle and prevent the machine from delivering any useful torque.

The present invention has as an object to provide a rotary hydrodynamic machine having greater efficiency than the prior machines.

Another object is to reduce the slip which is inherent in all hydrodynamic machines.

Another object is to provide a radial hydrodynamic machine in which the deflection of the parts is less than in the prior machines.

Another object is to provide a hydrodynamic machine having a valving mechanism which will enable it when functioning as a motor to deliver its full torque at all speeds and when stalled.

Another object is to provide a radial hydrodynamic machine which is more compact than the prior machines.

Other objects and advantages will appear from the description hereinafter given of hydrodynamic machines in which the invention is embodied.

According to the invention in its general aspect and as ordinarily embodied in practice, a hydrodynamic machine is provided with a rotatable cylinder barrel having a plurality of cylinders formed therein and communicating with passages extending through a face formed upon or near the end of the cylinder barrel, a piston fitted in each cylinder, means for reciprocating the pistons in response to rotation of the cylinder barrel, a valve member or seat having upon one end thereof a surface complementary to said face and adapted to form therewith a substantially fluid tight joint, a port formed in said face at one side of the cylinder barrel axis for connecting said machine to an external circuit and adapted to have said passages register therewith successively as said cylinder barrel rotates so that the liquid in said port is under a pressure which tends to separate said valve member and said cylinder barrel, and the forces which are exerted by the liquid in the valve port and between the valve member and the cylinder barrel and which tend to separate the valve member and the cylinder barrel are opposed by a plurality of forces which are exerted by hold-up devices and whose result-

ant is substantially coincident with and somewhat greater than the resultant of the forces tending to separate the valve member and the cylinder barrel.

According to the invention in another aspect, the cylinder barrel is rotatably supported by bearings which restrain it from axial movement, and means are provided to exert upon the cylinder barrel a force which is proportional to the pressure in the valve port and opposite to the force which holds the valve member against the cylinder barrel to thereby relieve the bearings of at least a part of the thrust imposed thereon.

According to the invention in another aspect, the valve seat is so supported that it may move transversely of the cylinder barrel axis and thereby prevent annular grooves from being worn in its face or in the end of the cylinder barrel.

The invention is exemplified by the pumps shown somewhat schematically in the accompanying drawings in which the views are as follows:

Fig. 1 is a vertical longitudinal section through a pump in which the invention is embodied, the section being taken on the irregular line 1—1 of Fig. 3 and certain parts being shown in full.

Fig. 2 is a sectional plan view taken on the irregular line 2—2 of Fig. 1 and with certain parts shown in full.

Fig. 3 is a transverse section taken on the irregular line 3—3 of Fig. 1.

Fig. 4 is a transverse vertical section taken on a line 4—4 of Fig. 1.

Fig. 5 is an end view on a larger scale of the valve seat shown in Figs. 1 to 4.

Fig. 6 is a central longitudinal section through a pump which differs from the pump shown in Fig. 1 in that it is larger, its pistons and cylinders are radial and it is provided with different means for holding the valve member against the end of the cylinder barrel and with means for relieving the thrust on the cylinder barrel bearings.

Fig. 7 is a transverse section taken on a line 1—1 of Fig. 6.

Fig. 8 is a transverse section taken on the line 8—8 of Fig. 6.

Fig. 9 is a view on a larger scale showing the valve member and the rear casing head removed from the casing, the view being taken in the direction of the arrows 9—9 on Fig. 6.

Fig. 10 is a longitudinal section through the valve member and the rear casing head taken on the line 10—10 of Fig. 9.

Fig. 11 is a partial longitudinal section through a pump which is similar to the pump shown in Fig. 6 and in which the axial components of the pumping forces are utilized to relieve the thrust on the cylinder barrel bearings.

Fig. 12 is a view similar to Fig. 10 but showing a different type of hold-up motor for urging the valve member against the end of the cylinder barrel.

The invention may be embodied in any radial type pump and in some pumps of the axial type but, for the purpose of illustration, it has been shown embodied in a pump of the type in which the pistons and cylinders are arranged in a cylinder barrel at an angle to the axis thereof and the outer ends of the pistons engage an annular reaction surface which is eccentric to the cylinder barrel and makes contact with each piston upon a single spot offset from the piston axis so that rotation of the cylinder barrel causes each piston to reciprocate and rotate in its cylinder. Since this type of pump is fully illustrated

and described in Patents Nos. 2,074,068 and 2,105,454, only so much of each pump has been shown as is necessary to an understanding of the present invention.

Figs. 1 to 5

The pump shown in these figures has its mechanism arranged within a casing 1 which is provided with a separable front head 2 and a separable rear head 3. Casing 1 has a cylinder barrel 4 rotatably supported therein by means of two bearings either or both of which may be capable of preventing cylinder barrel 4 from being moved axially by the pressure created by the pump and which have been shown as a ball bearing 5 and a thrust bearing 6.

Bearing 5 is carried by casing 1 and fitted upon a hollow hub 7 which is formed upon the rear end of cylinder barrel 4. Bearing 6 is carried by front head 2 and fitted upon a hub 8 which is formed upon the front end of cylinder barrel 4 and has a shaft 9 fixed thereto and extending outward through front head 2 for connection to a suitable source of power.

Cylinder barrel 4 has a plurality of radial cylinders 10 formed therein and a piston 11 fitted in each cylinder and extending beyond the periphery of cylinder barrel 4, the pistons and cylinders being slightly inclined to the axis of the cylinder barrel. While the number of cylinders may be varied to vary the volumetric capacity of the pump, cylinders 10 have been shown arranged in five equally spaced axial rows of two cylinders each.

The cylinders in each row communicate with a passage 12 formed in cylinder barrel 4 and extending rearward through a face 13 which is formed upon the rear end of cylinder barrel 4 exactly at right angles to the axis thereof and which forms a substantially fluid tight joint with a non-rotatable valve member or seat 14. Hub 7 may be solid and have face 13 formed upon its rear end but it has been shown as being hollow and extending around face 13 and valve seat 14 has been shown as having the front part thereof cylindrical and arranged within hub 7 in order to reduce the overall length of the pump and to reduce the compression slip, that is, to reduce the amount of liquid that is compressed during one half-revolution of the cylinder barrel and expands during the other half-revolution.

The rear end of each passage 12 constitutes a cylinder barrel port which, when cylinder barrel 4 is rotated, registers alternately with two approximately crescent shaped ports 15 and 16 formed in valve seat 14 and communicating, respectively, with two passages 17 and 18 extending rearward therethrough. The arrangement is such that valve seat 14 coacts with the rear end of cylinder barrel 4 to form a valve for controlling the flow of liquid to and from cylinders 10.

The outer ends of piston 11 engage the annular inner surface of a thrust member 20 which is rotatably supported by a displacement varying member or slide block 21. For the purpose of illustration, thrust member 20 has been shown as being annular and as being supported within slide block 21 by a needle bearing 22. Axial movement of thrust member 20 is limited in any suitable manner as by means of a flange 23 formed on cylinder barrel 4 directly behind bearing 6 and by a ring 24 fitted upon hub 7.

Slide block 21 is adapted to be shifted transversely of the axis of cylinder barrel 4 to vary the displacement of the pump but it is restrained

by casing 1 from movement in any other direction. As shown in Fig. 3, slide block 21 is adapted to be moved toward the left by a cam 27 having its opposite ends connected to two pistons 28 and 29 which are fitted, respectively, in two cylinders 30 and 31 fixed to casing 1 in alignment with each other.

Cam 27 has one of its faces inclined and in engagement with a contact 32 carried by slide block 21 and its opposite face arranged parallel to its path and in engagement with the flat inner end of a screw 33 which is threaded through the wall of casing 1 to prevent cam 27 from being deflected.

Slide block 21 is adapted to be shifted toward the right by a piston 34 fitted in a cylinder 35 which is carried by casing 1 and adapted to have motive liquid supplied thereto through a channel 36 from a source not shown, it being understood that pumps of this type ordinarily have a gear pump arranged in the casing thereof and driven in unison therewith. Slide block 21 may also be urged toward the right by a spring 37 which is arranged around cylinder 35 and holds contact 32 against cam 27 when servomotor 34-35 is deenergized.

The arrangement is such that, when cam 27 is in the position shown in Fig. 3, piston 34 and/or spring 37 will hold contact 32 in engagement with the center of cam 27 and thrust member 20 will be concentric with cylinder barrel 4 so that rotation of cylinder barrel 4 will not cause any reciprocation of pistons 11 and no liquid will be delivered by the pump.

When cylinders 30 and 35 are supplied with liquid at the same pressure and cylinder 31 is opened to drain, piston 28 will move cam 27 upward and cause it to shift slide block 21 toward the left and piston 34 will eject liquid from cylinder 35. Thrust member 20 will then be eccentric to cylinder barrel 4, and if cylinder barrel 4 is rotated in a clockwise direction as indicated by the arrow in Fig. 3, the pistons 10 in the lower half of cylinder barrel 4 will move progressively outward and draw liquid into their cylinders through passages 12 from port 16 and the pistons in the upper half of cylinder barrel 4 will be forced progressively inward and eject liquid from their cylinders through passages 12 into port 15.

When cylinders 31 and 35 are supplied with liquid and cylinder 30 is opened to drain, piston 29 will move cam 27 downward and then piston 34 will shift slide block 21 toward the right so that thrust member 20 is eccentric to cylinder barrel 4. Then rotation of cylinder barrel 4 in a clockwise direction will cause the pistons 10 in the upper half of cylinder barrel 4 to move progressively outward and draw liquid into their cylinders from port 15 and the pistons in the lower half of cylinder barrel 4 to be forced progressively inward and eject liquid from their cylinders into port 16 and thereby cause the pump to deliver liquid in a direction opposite to that in which it delivers liquid when slide block 4 is shifted toward the left from its neutral position.

If valve port 16 is connected to a source of motive liquid and thrust member 20 is shifted toward the left from its central position, the motive liquid will force the pistons 11 in the lower half of cylinder barrel 4 outward against the annular inner surface of thrust member 20 and thereby cause cylinder barrel 4 to rotate in the direction of the arrow on Fig. 3 due to thrust member 20 being eccentric to cylinder barrel 4. Each piston 11 will be moved progressively out-

ward by the liquid and impart rotary motion to cylinder barrel 4 during the half-revolution in which its cylinder is in communication with port 16 and then it will be moved progressively inward by thrust member 20 and exhaust liquid from its cylinder during the half-revolution in which its cylinder is in communication with port 15. Therefore, when adjusted and supplied with motive liquid in this manner, the machine will function as a motor and cause shaft 9 to rotate in a clockwise direction in respect to Fig. 3. The direction of rotation of shaft 9 may be reversed either by shifting thrust member 20 toward the right from its central position or by directing the motive liquid into port 15 instead of into port 16.

Regardless of whether the machine functions as a pump or as a motor, the liquid in one of the valve seat ports is under a high pressure, the liquid in the other valve seat port is under a low, zero or negative pressure, minute quantities of liquid will escape from the high pressure port and spread over face 13 and the end of valve seat 14 to form a lubricating film therebetween, the pressure prevailing in the high pressure port will extend into the lubricating film, and the pressure prevailing in one or both the ports and in the film will tend to move the valve seat and the cylinder barrel away from each other.

Due to the pressure being very high in one valve seat port and very low or absent in the other valve seat port, the film pressure varies from a high pressure at the edge of the high pressure port to a low or zero pressure at the edge of the other port and to zero at the outer edge of the valve seat. Consequently, the center of pressure is not on the center of the valve seat but near the center of a high pressure area which extends around the high pressure port.

In practice, this center of pressure is determined as closely as possible by calculation and then accurately established by experimentation, it being understood that the center of pressure is on one side of the cylinder barrel axis when one port is the high pressure port and on the other side of the cylinder barrel axis when the other port is the high pressure port. For example, the center of pressure in the machine shown is approximately at the center of the inner edge of the high pressure port. That is, when port 15 is the high pressure port, the center of pressure will be at or near the inner edge of that port upon a line passing through the centers of both ports and the axis of the machine as indicated at 38 in Fig. 5 and, when port 16 is the high pressure port, the center of pressure is on that line at or near the edge of port 16 as indicated at 39 in Fig. 5.

The machines heretofore provided with flat valve seats are ordinarily of the axial type, the valve seats are fixed in stationary positions and the cylinder barrel is held against the valve seat either by the pistons or by a servo-motor arranged coaxial with the cylinder barrel.

When the cylinder barrel is held against the valve seat by the pistons, the design and size of the valve seat is limited and the force exerted by the pistons varies due to the fact that the number of effective pistons varies in accordance with the number of cylinders in communication with the high pressure port at any given instant. For example, if the cylinder barrel contains seven cylinders, the number of cylinders in communication with the high pressure port will vary alternately between 3 and 4 so that the number of

pistons urging the cylinder barrel against the valve seat will vary from 3 to 4.

When the cylinder barrel is held against the valve seat by a coaxial servo-motor, the force exerted thereby is centered on the axis of the cylinder barrel but the force tending to separate the valve seat and the cylinder barrel is centered at a point which is spaced a considerable distance from the cylinder barrel axis. Consequently, the cylinder barrel bears too heavily against the low pressure side of the valve seat and causes undue wear and it does not bear heavily enough against the high pressure side of the valve seat so that a considerable volume of liquid leaks from between the cylinder barrel and the valve seat.

The present invention overcomes the above objectionable characteristics by restraining the cylinder barrel from axial movement and urging the valve seat against the cylinder barrel with a force which is proportional to the pressure of the motive liquid and centered at the center of the pressure tending to separate the cylinder barrel and the valve seat.

As shown, cylinder barrel 4 is restrained from axial movement by thrust bearing 6. The pressure acting upon the pressure area tends to move valve seat 14 rearward, and valve seat 14 is urged against face 13 by a force which is proportional to the pressure prevailing in the high pressure port and which is applied directly against the center of pressure 38 or 39 in order to prevent valve seat 14 from tending to tilt, thereby preventing undue wear of the abutting faces and keeping the leakage from between the cylinder barrel and the valve seat to a very low rate.

It has been found in practice that the leakage from between the cylinder barrel and the valve seat is only a small fraction of the corresponding leakage in any prior hydrodynamic machine of the same size and that the frictional drag on the cylinder barrel is considerably less than in the prior machines which are provided with pintles. Consequently, the machine has a much greater efficiency than could be obtained heretofore. Also, the film between cylinder barrel face and valve seat is not squeezed out during operation at extremely low speeds or even when stalled. Hence the machine when functioning as a motor is capable of exerting its full torque at slow speeds and when stalled.

In a pump of sufficient size, valve seat 14 may be held against face 13 by a plurality of hold-up motors which are so arranged that the resultant of the forces exerted thereby lands directly upon the center of pressure as shown in Figs. 6 to 10.

In a reversible pump which is small enough to discharge its entire output through a single channel, the valve seat may be held against the cylinder barrel by one or the other of two hold-up motors. If there is sufficient room, each of the motors may be arranged parallel to the cylinder barrel axis and in alignment with a pressure center 38 or 39 but, if the pump is very small, room may be obtained for each of these hold-up motors by arranging them at an angle to the cylinder barrel axis and so locating them that a component of the force exerted by each hold-up motor lands directly upon a pressure center 38 or 39. When the hold-up motor is arranged at an angle to the cylinder barrel axis, the radial component of the force exerted by the motor may be utilized to cause the valve

seat to have a slight radial movement in response to variations in pump pressure and thereby prevent annular grooves from being worn in the abutting faces of the valve seat and the cylinder barrel.

As shown, the rear part of valve seat 14 is rectangular and arranged loosely within a rectangular opening 40 (Fig. 4) formed in the rear wall 41 of casing 1. Two pins 42 and 42^a are arranged in two recesses formed in opposite sides of the rectangular part of valve seat 14 upon opposite sides of the horizontal center line thereof, and the outer ends of pins 42 and 42^a engage, respectively, two stacks of flat leaf springs 43 and 43^a which are arranged, respectively, in suitable openings 44 and 44^a formed in rear wall 41 upon opposite sides of opening 40, pins 42 and 42^a preferably being so located that the axis of each pin passes through a pressure center 38 or 39 as shown in Fig. 5.

The arrangement is such that downward movement of valve seat 14 is prevented by the lower edge of opening 40 and lateral movement thereof is resisted by springs 43 and 43^a which will yield and permit it to move slightly toward the right or left in respect to Fig. 4 when it is subjected to a sufficient lateral force.

The force for urging valve seat 14 against face 13 is supplied by one or the other of two hold-up motors the axes of which are inclined in opposite directions to the cylinder barrel axis and pass, respectively, through pressure centers 38 and 39.

As best shown in Fig. 2, one of the hold-up motors has its piston 45 fitted in a cylinder 46 which is adapted to be connected to one side of an external circuit as by means of a channel 47. Piston 45 has a bore 48 formed therein and communicating with passage 17 in valve seat 14 through a hollow connecting rod 49 which functions both as a connecting rod for transmitting force from piston 45 to valve seat 14 and as a channel for conveying liquid between passage 17 and cylinder 46.

The rear end of connecting rod 49 is substantially spherical and fitted into a complementary seat formed in piston 45 around bore 48 so as to form a fluid tight universal joint between piston 45 and rod 49. The front end of rod 49 is also substantially spherical and forms a fluid tight joint with a complementary seat which is formed in valve seat 14 around passage 17 and preferably has its center located at the intersection of a line passing transversely of the machine through pin 42 and a line passing longitudinally of the machine through pressure center 38.

The spherical ends of rod 49 are initially held in contact with their seats and valve seat 14 is initially urged against face 13 by a helical compression spring 50 which is arranged in cylinder 46 and acts upon piston 45 to thereby maintain fluid tight joints at the ends of rod 49 and between valve seat 14 and face 13.

Since the second hold-up motor is exactly the same as motor 45-49, it has been shown only in dotted lines and the parts thereof have been indicated by the same reference numerals with the exponent "a" added thereto so that a complete description thereof is unnecessary.

The cylinder 46^a of the second hold-up motor communicates with a channel 47^a by means of which it may be connected to the other side of an external circuit, and the connecting rod 75 49^a thereof engages a spherical seat which is

formed in valve seat 14 around passage 18 and preferably has its center located at the intersection of a line passing transversely of the machine through pin 42^a and a line passing longitudinally of the machine through pressure center 39.

The arrangement is such that the machine may discharge liquid through one hold-up motor into one side of an external circuit and be supplied with liquid through the other hold-up motor from the other side of the external circuit, and the pressure in each hold-up cylinder will be equal to the pressure prevailing in the valve seat port with which that cylinder communicates.

The pressure in the cylinder 46 or 46^a communicating with the high pressure port will cause the piston 45 or 45^a therein to urge connecting rod 49 or 49^a against valve seat 14 with a force proportional to the pressure prevailing in the high pressure port. The axial component of this force will press valve seat 14 against face 13 and, since the axial component is applied to valve seat 14 in alignment with the pressure center, it will cause the entire end surface of valve seat 14 to bear evenly against face 13.

The radial component of this force will act upon valve seat 14 along the axis of pin 42 or 42^a and will cause springs 43 or 43^a to yield slightly and permit valve seat 14 to move radially and thereby cause each point on the end surface thereof to bear against a different point on face 13. Valve seat 14 will thus move across face 13 in one direction or the other in response to a variation in pump pressure but the maximum distance that it can move in either direction is very limited, for example, it is limited to about ten thousandths of an inch in a small pump.

Figs. 6 to 10

The pump in these figures has its mechanism arranged within a casing 51 which is provided with a separable front head 52 and a separable rear head 53. Casing 51 has a cylinder barrel 54 rotatably supported therein by means of two bearings either or both of which may also resist axial movement of cylinder barrel 54. As shown, the rear end of cylinder barrel 54 is supported by a ball bearing 55 and the front end thereof is supported by a thrust bearing 56.

Bearing 55 is carried by casing 51 and fitted upon a hollow hub 57 which is formed upon the rear end of cylinder barrel 54. Bearing 56 is carried by front head 52 and fitted upon a hub 58 which is formed upon the front end of cylinder barrel 54 and has a shaft 59 fixed thereto and extending outward through front head 52 for connection with suitable source of power.

Cylinder barrel 54 has a plurality of radial cylinders 60 formed therein and a piston 61 fitted in each cylinder and extending beyond the periphery of cylinder barrel 54. The cylinders are ordinarily arranged in both circumferential and axial rows according to the usual practice and the number of rows or the number of cylinders in each row may be varied to vary the displacement of the pump. In Fig. 6, each axial row has been shown as consisting of two cylinders and each circumferential row may contain five cylinders as shown in Fig. 3.

The cylinders in each axial row communicate with a passage 62 formed in cylinder bar-

rel 54 and extending rearward through a face 63 which is formed upon the rear end of cylinder barrel 54 exactly at right angles to the axis thereof and forms a substantially fluid tight joint with a non-rotatable valve member 64. For the purpose of illustration, face 63 has been shown arranged within hub 57 and as being flat.

Valve member 64 has its front part sufficiently reduced in diameter to clear the inner wall of hub 57 and its rear part arranged within a recess 65 which is formed in rear head 53. In order that valve member 64 may be supported within recess 65 and be free to adjust itself to face 63 and thereby maintain a substantially fluid tight joint therebetween, its rear part is made somewhat smaller than recess 65 and provided with a small annular flange 66 which is arranged near the center of gravity of valve member 64 and loosely fitted in recess 65, a notch 67 (Fig. 9) being formed in flange 66 to permit liquid to drain from the rear end of recess 65.

Rotation of valve member 64 may be prevented in any suitable manner, such as by means of a pin fixed in end head 53 and loosely fitted in a hole formed in valve member 64, but it has been shown restrained from rotation by a key 68 fixed in end head 53 and loosely fitted in a suitable notch formed in flange 66, it being understood that only a very slight movement of valve member 64 is necessary to enable it to adjust its front end to face 63 on cylinder barrel 54.

The rear end of each passage 62 constitutes a cylinder barrel port which, during rotation of cylinder barrel 54, registers alternately with two approximately crescent shaped ports 69 and 69^a formed in valve member 64 upon opposite sides of the cylinder barrel axis so that the valve member coats with the rear end of the cylinder barrel to form a valve for controlling the flow of liquid drawn into and ejected from cylinders 60 by pistons 61 during rotation of cylinder barrel 54.

Each piston 61 is provided upon its outer end with an enlarged head having an arcuate contact face formed thereon. The contact faces on the heads of the pistons in each circumferential row are engaged by the conical inner surface of a thrust ring 71 which engages each contact face upon a single spot offset from the piston axis.

Thrust rings 71 are fixed within a substantially cylindrical member and form therewith a thrust member 72 for causing reciprocation of pistons 61 during rotation of cylinder barrel 54. Thrust member 72 may be an integral structure but rings 71 have been shown as individual elements and retained in position by suitable spacer rings in order to facilitate manufacture and selection of materials.

Thrust member 72 is rotatably supported, as by means of bearings 73 and 74, within a displacement varying member or slide block 75 which is shiftable transversely in a horizontal plane but is restrained by casing 51 from movement in any other direction. Slide block 75 may be shifted by any suitable means such, for example, as the displacement varying mechanism shown in Fig. 3.

When slide block 75 is in its central or neutral position at which time it is concentric with cylinder barrel 54, the pump is at zero stroke and no liquid will be delivered thereby. When slide block 75 is shifted in one direction or the other, the pump will deliver liquid in a direction and at a rate dependent upon the direction and the

distance slide block 75 is shifted from its neutral position.

When cylinder barrel 54 is rotated and slide block 75 is at one side of its central or neutral position, pistons 61 will move progressively outward during one half-revolution of cylinder barrel 54 and be forced progressively inward by thrust rings 71 during the other half-revolution of cylinder barrel 54. If cylinder barrel 54 is rotated in one direction and slide block 75 at 10 at one side of its neutral position, the inward moving pistons will eject liquid from their cylinders through passage 62 into port 69 and the outward moving pistons will draw liquid into their cylinders through passage 62 from port 69^a. If cylinder barrel 54 is rotated in the opposite direction or if slide block 75 is shifted to the other side of its neutral position, pistons 61 will draw liquid from port 69 and discharge liquid into port 69^a.

As previously explained, the pressure in one port 69 or 69^a is higher than the pressure in the other port regardless of the direction of liquid flow or whether the machine is functioning as a pump or as a motor, liquid escapes from the high pressure port and forms a lubricating film between valve member 64 and face 63 on cylinder barrel 54, the forces exerted by the liquid in one or both of the ports and in the film tend to move cylinder barrel 54 and valve member 64 away from each other, and the resultant of these forces is upon a line passing through a point between the cylinder barrel axis and the center of the high pressure port as indicated by point 38 or 39 on Fig. 5.

Cylinder barrel 54 is restrained from axial movement by its bearings and, if the pump is of such size that an excessive thrust is imposed upon the cylinder barrel bearings due to the forces exerted upon the cylinder barrel by the liquid, the thrust on the bearings is relieved by means to be presently described.

Valve member 64 is held against face 63 by a plurality of hold-up motors which are so arranged and proportioned that the resultant of the forces exerted thereby is coincident with and opposite to the resultant of the forces tending to move valve member 64 away from face 63. As shown, valve member 64 is urged against face 63 by a hold-up motor which is arranged at the center of the valve member and by two pairs of hold-up motors which are arranged at opposite sides of the center motor and connected, respectively, to ports 69 and 69^a.

The center motor has its piston 76 in engagement with the rear end of valve member 64 and fitted in a cylinder 77 which is formed in rear head 53 and contains a spring 78 for initially holding piston 76 against valve member 64 and for assisting in initially holding valve member 64 against face 63.

Cylinder 77 is connected by a channel 79 to a channel 80 which has an automatically operating shuttle valve 81 fitted therein to control communication between channel 80 and two channels 82 and 82^a which are connected to opposite ends of channel 80. Channels 82 and 82^a extend transversely of end head 53 and are adapted to be connected to opposite sides of an external circuit as by means of pipes 83 and 83^a. The liquid in the channel 82 or 82^a containing the higher pressure will move valve 81 against the opposite end of channel 80 and cause it to block communi-

cation between cylinder 77 and the channel 82 or 82^a containing the lower pressure.

The arrangement is such that piston 76 is forced against valve member 84 by liquid supplied to cylinder 77 from the channel 82 or 82^a in which the pressure is the higher but the high pressure liquid is prevented by valve 81 from flowing into the other channel 82 or 82^a.

Each of the pair of hold-up motors arranged above hold-up motor 76—77 has a hollow piston 85 fitted in a cylinder 86 which is formed in end head 53 and connected by a channel 87 to channel 82. The opening through piston 85 communicates through a hollow connecting rod 88 with a channel 89 which is formed in valve member 64 and communicates with port 69.

The ends of connecting rod 88 are spherical and engage complementary seats formed in valve member 64 and in piston 85 so as to form fluid 20 tight joints between piston 85 and valve member 64 and to permit valve member 64 to adjust itself to face 63 on cylinder barrel 54. The joints are initially kept tight by a spring 90 which is arranged in cylinder 86 to urge piston 85 against connecting rod 88 and thereby urge valve member 64 against face 63 on cylinder barrel 54.

The pair of hold-up motors arranged below the center hold-up motor are exactly the same as hold-up motors 85 and 88 and are connected to port 69^a and channel 82^a in exactly the same manner that motors 85—88 are connected to port 69 and channel 82. Consequently, like parts have been indicated by like reference numerals with the exponent "a" added thereto and further description is deemed unnecessary.

The arrangement is such that channels 89, hollow connecting rods 88, hollow pistons 85, cylinders 86 and channels 87 and 82 are adapted to connect port 69 to one side of an external circuit and channels 89^a, hollow connecting rods 88^a, hollow pistons 85^a, cylinders 86^a and channels 87^a and 82^a are adapted to connect port 69^a to the other side of an external circuit.

When the pump is performing usual work and pistons 61 are discharging liquid into port 69, the pump will create pressure which will act upon pistons 85 and shift valve 81 to the opposite end of channel 80 so that the pressure can act upon piston 76, thereby causing pistons 76 and 85 to urge valve member 64 against face 63 on cylinder barrel 54 with forces which are proportional to pump pressure.

If the pump is reversed so that pistons 61 are discharging liquid into port 69^a, the pump will create pressure which will act upon pistons 85^a, shift valve 81 and act upon piston 76 and thereby cause pistons 76 and 85^a to urge valve member 64 against face 63 on cylinder barrel 54 with forces which are proportional to pump pressure.

The hold-up motors are so proportioned and arranged that the resultant of the forces exerted by the three hold-up motors communicating with the high pressure port is coincident with and somewhat greater than the resultant of the forces exerted by the liquid in the high pressure port and in the film around the high pressure port. Consequently, valve member 64 is positively held against face 63 and forms a substantially fluid tight joint therewith.

If the pump is of such size that the forces which urge the cylinder barrel forward would impose an excessive thrust upon the cylinder barrel bearings, the pump is provided with hydraulic means for urging the cylinder barrel rearward with a

force which is proportional to pump pressure and substantially equal to or slightly less than the force which tends to move the cylinder barrel forward.

Such hydraulic means may assume various forms but, for the purpose of illustration, front head 52 has been shown as having a cylinder 91 formed therein concentric with shaft 59 and supplied with liquid from the high pressure side of the pump through a channel 92 and other channels not shown.

Cylinder 91 has arranged therein an annular piston 93 which has as close a running fit with the wall thereof as is commercially practical. The rear end of piston 93 is closely fitted to the end of hub 58 and initially held in contact therewith by a plurality of springs 94 each of which is arranged within piston 93 around a bolt 95 threaded into hub 58 so that annular piston 93 is caused to rotate with cylinder barrel 54.

When liquid is supplied to cylinder 91, it will force piston 93 against hub 58 and cause it to form a substantially fluid tight joint therewith. The clearance between piston 93 and the wall of cylinder 91 will permit liquid to leak at a very slow rate from cylinder 91 but this leakage is so slight that it has practically no effect upon the efficiency of the pump.

The arrangement is such that cylinder barrel 54 is urged rearward by the liquid in cylinder 91 acting upon piston 93 which is so proportioned that the force exerted thereby is substantially equal to or slightly less than the sum of the forces which tend to move cylinder barrel 54 forward. Since the forces which urge cylinder barrel 54 forward are substantially proportional to pump pressure and are opposed by a force which is nearly equal to the sum of those forces and is proportional to pump pressure, cylinder barrel 54 is in a nearly balanced condition at all times so that the only thrust imposed upon one or both of the cylinder barrel bearings is due to the small unbalanced forces.

Fig. 11

The pump partially illustrated in this figure differs from the pump shown in Fig. 6 in that the thrust ring 71 nearer the front of the pump has been reversed and moved forward from the position shown in Fig. 6. Since the two pumps may be otherwise identical, like parts have been indicated by like reference numerals and further description thereof is unnecessary.

When the pump is performing useful work, pistons 61 are permitted to move outward during one half-revolution of cylinder barrel 54 and are forced inward during the other half-revolution of cylinder barrel 54 by thrust rings 71 to thereby cause them to pump liquid from one to the other side of a hydraulic circuit as previously explained. Since the contact surfaces on the piston heads and on the thrust ring are bevelled and each piston is engaged by its thrust ring at a point offset from the piston axis, the pumping force transmitted to each piston from its thrust ring may be resolved into a radial component which forces the piston inward and an axial component which tends to move the piston axially of the pump and thereby tends to move the cylinder barrel axially.

If the thrust rings engage one half of the pistons at one side of the axes thereof and engage the other half of the pistons at the other side of the axes thereof as shown in Fig. 6, the axial components of the pumping forces cancel each

other so that no axial force is transmitted to the cylinder barrel.

If the thrust rings engage all of the pistons upon that side of the piston axes toward the front of the pump as shown in Fig. 11, the axial components of the pumping forces will be transmitted to the cylinder barrel and tend to move it rearward, thereby relieving the cylinder barrel bearings of at least a part of the thrust imposed thereon by the forces which tend to move the cylinder barrel forward.

It has previously been pointed out that a small pump may be provided with cylinder barrel bearings capable of withstanding the thrust imposed thereon by the forces tending to move the cylinder barrel forward. In larger pumps, the thrust on the cylinder barrel bearings may be relieved by utilizing the axial components of the pumping forces as shown in Fig. 11, by providing the pump with a hydraulic motor such as the motor 91-93 shown in Fig. 6, or by both of these methods.

Fig. 12

The mechanism shown in this figure differs from the mechanism shown in Fig. 10 in that the hollow connecting rods are omitted and the pistons of the upper and lower hold-up motors are free to tilt slightly in their cylinders. Since the mechanism is otherwise exactly the same as the mechanism shown in Fig. 10, like parts and passages have been indicated by like reference numerals and no further description thereof is necessary.

As shown, a valve member 164 is provided with diametrically opposed ports 69 and 69^a and arranged in a recess 65 formed in an end head 53 which has a center hold-up motor 16-71, upper and lower hold-up motor cylinders 86 and 86^a and channels 79, 80, 82, 82^a, 87 and 87^a arranged therein as previously explained, channel 80 having a shuttle valve 81 arranged therein as shown in Fig. 6 but not shown in this figure.

Each hold-up cylinder 86 has arranged therein a hollow piston 185 which is somewhat smaller in diameter than cylinder 86 and provided with suitable piston rings for forming a fluid tight joint between piston 185 and the wall of cylinder 86. The opening through piston 185 communicates with a passage 189 which is formed in valve member 164 and extends from the flat rear end thereof into communication with port 69.

The hold-up pistons could be formed integral with valve member 164 but a valve member with integral pistons would be very difficult to manufacture. Therefore, they are ordinarily made separately and the front part of each piston 185 is reduced in diameter and provided with a flat end to engage the rear end of valve member 164 and form therewith a substantially fluid tight joint around passage 189. Contact between the front end of piston 185 and the rear end of valve member 164 is initially maintained by a spring 190 which is arranged in cylinder 86 and urges piston 185 forward.

The lower pair of hold-up motors are exactly the same as the upper pair and are connected to port 69^a in the same manner that cylinders 86 are connected to port 69. Consequently, corresponding parts and passages have been indicated by corresponding reference numerals with the exponent "a" added thereto and further description is unnecessary.

The hold-up mechanism functions in the same manner as the hold-up mechanism shown in Figs. 6 to 10 except that, when the hold-up mo-

tors tilt valve member 64 to form a fluid tight joint between its front end and the face 63 on cylinder barrel 54, pistons 185 will tilt in cylinders 86 due to the clearance between the peripheries of the pistons and the walls of the cylinders, it being understood that the movement of valve member 164 is very slight and only enough to compensate for wear and for irregularities in manufacture.

The invention described herein is susceptible of various other modifications without departing from the scope of the appended claims in which the invention is defined as being applied to a pump but, since a hydrodynamic machine embodying the invention will function either as a pump or as a motor, the term "pump" is used in the claims as being synonymous with the term "motor" and the claims are intended to cover a hydrodynamic machine regardless of whether it is used as a pump or as a motor.

The invention is hereby claimed as follows:

1. In a pump, the combination of a rotatable cylinder barrel restrained from axial movement and having a recess formed in the rear end thereof with its end wall substantially at right angles to the axis of said cylinder barrel, pumping means arranged in said cylinder barrel and communicating with said recess through the end wall thereof, a valve member arranged in said recess and forming with the end wall thereof a valve for controlling the flow of liquid to and from said pumping means, a cylinder arranged in a stationary position for connection to an external circuit, a hollow piston fitted in said cylinder, a hollow connecting rod arranged upon said piston and engaging said valve member at said port for directing liquid from said valve member through said piston to said cylinder and for transmitting force from said piston to said valve member to thereby enable the liquid in said cylinder to cause said piston to urge said valve member against said end wall with a force proportional to pump pressure, and means independent of said connecting rod and said piston for preventing rotation of said valve member.

2. In a pump, the combination of a rotatable cylinder barrel restrained from axial movement and having pumping means arranged therein and passages extending from said pumping means through the rear end of said cylinder barrel, a valve member engaging the rear end of said cylinder barrel and forming therewith a valve for controlling the flow of liquid to and from said pumping means, a stationary cylinder arranged at an angle to the axis of said cylinder barrel and adapted to be connected to an external circuit, a hollow piston fitted in said cylinder, a hollow connecting rod arranged upon the axis of said cylinder and having its ends fitted into said piston and said valve member so that the liquid discharged by said pumping means is directed through said rod and said piston a force proportional to pump pressure the axial component of which urges said valve member against said cylinder barrel and the radial component of which tends to move said valve member radially, and yieldable means for supporting said valve member and for enabling said valve member to have a slight radial movement in response to a material variation in pump pressure.

3. In a pump, the combination of a rotatable cylinder barrel restrained from axial movement and having a recess formed in the rear end thereof with its end wall substantially at right

angles to the axis of said cylinder barrel, pumping means arranged in said cylinder barrel and communicating with said recess through the end wall thereof, a valve member arranged in said

5 recess and forming with the end wall thereof a valve for controlling the flow of liquid to and from said pumping means, a stationary cylinder arranged at an angle to the axis of said cylinder barrel and adapted to be connected to an external circuit, a hollow piston fitted in said cylinder, a hollow piston rod arranged upon the axis of said cylinder and having its ends fitted into said piston and said valve member so that the liquid discharged by said pumping means is directed through said rod and said piston to said cylinder and exerts upon said piston a force proportional to pump pressure the axial component of which urges said valve member against said end wall and the radial component of which tends to move said valve member radially, and yieldable means for supporting said valve member and for enabling said valve member to have a slight radial movement in response to a material variation in pump pressure.

20 4. In a pump, the combination of a rotatable cylinder barrel restrained from axial movement and having pumping means arranged therein and passages extending from said pumping means through the rear end of said cylinder barrel, a valve member engaging the rear end of said cylinder barrel and forming therewith a valve for controlling the flow of liquid to and from said pumping means, a stationary cylinder arranged at an angle to the axis of said cylinder barrel and adapted to be connected to an external circuit, a hollow piston fitted in said cylinder, a hollow piston rod arranged upon the axis of said cylinder and having its ends fitted into said piston and said valve member so that the liquid discharged by said pumping means is directed through said rod and said piston to said cylinder and exerts upon said piston a force proportional to pump pressure the axial component of which urges said valve member against said cylinder barrel and the radial component of which tends to move said valve member radially, and a plurality of leaf springs arranged upon opposite sides of said valve member for so supporting it that the radial component of said force will cause it to have a slight radial movement in response to a material variation in pump pressure.

45 5. In a pump, the combination of a rotatable cylinder barrel restrained from axial movement and having a recess formed in the rear end thereof with its end wall substantially at right angles to the axis of said cylinder barrel, pumping means arranged in said cylinder barrel and communicating with said recess through the end wall thereof, a valve member arranged in said recess and forming with the end wall thereof a valve for controlling the flow of liquid to and from said pumping means, a stationary cylinder arranged at an angle to the axis of said cylinder barrel and adapted to be connected to an external circuit, a hollow piston fitted in said cylinder, a hollow piston rod arranged upon the axis of said cylinder and having its ends fitted into said piston and said valve member so that the liquid discharged by said pumping means is directed through said rod and said piston to said cylinder and exerts upon said piston a force proportional to pump pressure the axial component of which urges said valve member against said end wall and the radial component of which tends to move said valve member radially, and a plu-

rality of leaf springs arranged upon opposite sides of said valve member for so supporting it that the radial component of said force will cause it to have a slight radial movement in response to a material variation in pump pressure.

6. In a pump, the combination of a rotatable cylinder barrel restrained from axial movement and having pumping means arranged therein and passages extending from said pumping means through the rear end of said cylinder barrel, a valve member engaging the rear end of said cylinder barrel and forming therewith a valve for controlling the flow of liquid to and from said pumping means, said valve member having formed therein two diametrically opposed arcuate ports with which each of said passages communicates alternately as said cylinder barrel rotates, a center cylinder arranged in a stationary position in alignment with the axis of said cylinder barrel, a piston fitted in said cylinder for urging said valve member against said cylinder barrel upon pressure liquid being supplied to said cylinder, other stationary cylinders spaced outward from said center cylinder and adapted to be connected to an external circuit, a hollow piston assembly fitted in each of said other cylinders and engaging said valve member in communication with one of said ports to transmit liquid between said pumping means and said other cylinders so that the pressure in said other cylinders causes said piston assemblies to urge said valve member against said cylinder, and means for automatically directing liquid to said center cylinder from the other cylinder in which the pressure is the highest.

7. In a pump, the combination of a rotatable cylinder barrel restrained from axial movement and having pumping means arranged therein and passages extending from said pumping means through the rear end of said cylinder barrel, a valve member engaging the rear end of said cylinder barrel and forming therewith a valve for controlling the flow of liquid to and from said pumping means, said valve member having formed therein two diametrically opposed arcuate ports with which each of said passages communicates alternately as said cylinder barrel rotates, a center cylinder arranged in a stationary position in alignment with the axis of said cylinder barrel, a piston fitted in said cylinder for urging said valve member against said cylinder barrel upon pressure liquid being supplied to said cylinder, other stationary cylinders spaced outward from said center cylinder and adapted to be connected to an external circuit, a hollow piston assembly fitted in each of said other cylinders and engaging said valve member in communication with one of said ports to transmit liquid between said pumping means and said other cylinders so that the pressure in said other cylinders causes said piston assemblies to urge said valve member against said cylinder, means for automatically directing liquid to said center cylinder from the other cylinder in which the pressure is the highest, and means independent of said piston assemblies for preventing rotation of said valve member.

8. In a pump, the combination of a rotatable cylinder barrel restrained from axial movement and having a recess formed in the rear end thereof with its end wall substantially at right angles to the axis of said cylinder barrel, pumping means arranged in said cylinder barrel and communicating with said recess through the end wall thereof, a valve member arranged in said recess and forming with the end wall thereof a valve for controlling the flow of liquid to and from said pumping means, said valve member having formed therein two diametrically opposed arcuate ports with which said pumping means communicates alternately as said cylinder barrel rotates, a center cylinder arranged in a stationary position in alignment with the axis of said cylinder barrel, a piston fitted in said cylinder for urging said valve member against said end wall upon pressure liquid being supplied to said cylinder, other stationary cylinders spaced outward from said center cylinder and adapted to be connected to an external circuit, a hollow piston assembly fitted in each of said other cylinders and engaging said valve member in communication with one of said ports to transmit liquid between said pumping means and said other cylinders so that the pressure in said other cylinders causes said piston assemblies to urge said valve member against said end wall, and means for automatically directing liquid to said center cylinder from the other cylinder in which the pressure is the highest.

9. In a pump, the combination of a rotatable cylinder barrel restrained from axial movement and having a recess formed in the rear end thereof with its end wall substantially at right angles to the axis of said cylinder barrel, pumping means arranged in said cylinder barrel and communicating with said recess through the end wall thereof, a valve member arranged in said recess and forming with the end wall thereof a valve for controlling the flow of liquid to and from said pumping means, said valve member having formed therein two diametrically opposed arcuate ports with which said pumping means communicates alternately as said cylinder barrel rotates, a center cylinder arranged in a stationary position in alignment with the axis of said cylinder barrel, a piston fitted in said cylinder for urging said valve member against said end wall upon pressure liquid being supplied to said cylinder, other stationary cylinders spaced outward from said center cylinder and adapted to be connected to an external circuit, a hollow piston assembly fitted in each of said other cylinders and engaging said valve member in communication with one of said ports to transmit liquid between said pumping means and said other cylinders so that the pressure in said other cylinders causes said piston assemblies to urge said valve member against said end wall, means for automatically directing liquid to said center cylinder from the other cylinder in which the pressure is the highest, and means independent of said piston assemblies for preventing rotation of said valve member.

WALTER FERRIS.
